UNITED STATES PATENT OFFICE.

JOHN M. LOEW, OF BROOKLYN, NEW YORK.

DESIGN FOR LOAF-BREAD.

SPECIFICATION forming part of Design No. 20,420, dated December 23, 1890.

Application filed November 7, 1890, Serial No. 370,698. Term of patent 7 years.

To all whom it may concern:

Be it known that I, JOHN M. LOEW, a citizen of the United States, residing at Brooklyn, in the county of Kings and State of New York, have invented and produced a new and original Design for Loaf-Bread, of which the following is a specification, reference being had to the accompanying drawing, forming part thereof, which represents a perspective view of a loaf formed in accordance with my design.

The general contour of the loaf is circular, and above a circular line A, concentric with and some distance removed from the base-line A', the upper side surfaces of the loaf

have the appearance of being bulged or swelled outward and upward.

The upper swelled surface of the loaf presents a series of essentially triangular figures B, and the space D between the triangular figures has a decidedly broken lumpy appearance, approximating that of a filling of puffed fabric.

I claim—

A design for loaf-bread, substantially as 25 herein shown and described.

JOHN M. LOEW.
